UNITED STATES PATENT OFFICE.

RAFAEL PADILLA, OF NEW YORK, N. Y.

DISPLAY DEVICE FOR ADVERTISING AND EDUCATIONAL PURPOSES.

Application filed March 11, 1921. Serial No. 451,610.

To all whom it may concern:

Be it known that I, RAFAEL PADILLA, a citizen of the Republic of Mexico, residing at New York city, in the county of New

5 York and State of New York, have invented new and useful Improvements in Display Devices for Advertising and Educational Purposes, of which the following is a specification.

10 This invention relates to devices for advertising and educational purposes and for the dissemination of news, etc., and is in many respects an improvement on and continuation of the invention set forth in my Patent No. 1,313,110, issued August 12, 1919.

One of the objects of the device is to provide mechanical means for operating rolls carrying a strip upon which is printed, pasted or otherwise secured or formed, matter to be displayed to the observer.

20 Another object is to produce a device whereby a phonograph may be utilized to give a lecture upon a subject and mechanical means operable in synchronism therewith may present visual representations of the subjects discussed.

Another object is to produce a device of this nature wherein the display rolls are automatically rewound when exhausted and at a much more rapid rate than they are moved during the display winding.

30 Another object is to provide a tension drive for the rolls to compensate for the varying rates of speed of the strip due to the increased or diminished size of the roll during winding and unwinding.

With these and other objects in view which will be apparent as the description proceeds, the invention resides in certain 40 novel construction and combination and arrangement of parts the essential features of which are hereinafter fully described, are particularly pointed out in the appended claims, and are illustrated in the accompanying drawings, in which:—

Figure 1 is a perspective view of a machine constructed according to my invention.

Figure 2 is a vertical section of the same.

Figure 3 is a fragmentary vertical sectional view showing the gear trains.

Figure 4 is a horizontal section taken substantially on line 4—4 of Figure 3.

Figure 5 is a horizontal sectional view taken substantially on line 5—5 of Figure 3.

Figure 6 is a view taken substantially on 55 line 6—6 of Figure 2 looking rearwardly.

Figure 7 is a fragmentary detail sectional view of one of the upper rollers and its operating mechanism.

Figure 8 is a similar view of one of the 60 lower rollers.

Figure 9 is an end view of one of the lower rollers.

Figure 10 is a detail of one of the rollers showing the strip fastening cleat. 65

Figure 11 is a detail view of the manual reverse and neutral lock.

Figure 12 is a detached view of one of the rolls and a portion of the display strip.

Figure 13 is a diagrammatic view showing the electrical equipment. 70

Like characters of reference refer to like parts in all views.

The general function of the device may be stated to be the dissemination of knowledge; but as this may seem vague and general, the matter will first be explained somewhat in detail. In using the device for advertising purposes, the machine may be installed in a show window or on a street 75 corner and the roll or rolls of flexible material which are fed up before the observer are provided with strips of advertising matter interspersed with strips setting forth the latest news items, or other matter of interest 80 or artistic value. 85

In rural districts where it is difficult or impossible to obtain competent teachers of various subjects the machine may be set up and operated by any person of ordinary 90 intelligence, and by having the rolls and phonograph records prepared by experts in the various subjects, the most advanced instruction may be given. The device would also prove helpful in giving instruction as 95 to improved methods to farmers, or in military tactics, aeroplane construction and operation for soldiers and sailors, or in air-brake construction for trainmen, and in various other places which will readily suggest themselves to various minds. 100

Referring in detail to the drawing, 10 represents the casing of the machine which may be constructed of any suitable material and

mounted upon casters or a suitable pedestal. The frame is provided in front with suitable display windows 11 and is provided with doors or other means permitting access to 5 the internal mechanism.

The interior of the casing is provided with 10 sockets to receive electric light bulbs 12 for illuminating the interior of the apparatus. Secured to any desirable portion of the 15 framework is a rheostat conventionally shown at 13, a fuse box 14, a switch 15, and a motor 16 all in circuit with any suitable source of electrical energy. The speed of the motor is controllable by the rheostat as 20 will be readily understood.

The motor shaft 17 has secured to it a 25 gear pinion 18 in mesh with a larger gear 19, wheels 18 and 19 being enclosed in a gear case 20 and running in oil. The shaft 21 of gear 19 is provided with a worm 22 in which are meshed worm gears 23 and 24 arranged on opposite sides of said worm so as to turn in opposite directions. The gears 23 and 24 are mounted on and adapted to operate upon 30 right shafts 25 and 26, respectively, which carry at their upper ends respective clutch members 27 and 28 keyed to them and movable longitudinally thereon.

The clutch members 27 and 28 are provided 35 with annular grooves 29 into which extend fingers 30 formed as bifurcations on opposite ends of a rock lever 31 mounted to rock on a pivot 32 arranged midway between the clutch members 27 and 28. The rear end 40 of lever 31 is extended beyond the member 27 for a purpose to be hereinafter set forth. For the present it will be sufficient to state that rocking of lever 31 will raise one or the other of clutch members 27 and 28 into engagement with a respective clutch member 45 and lower the other out of engagement.

Two shafts 33 and 34 are respectively mounted in axial alignment with shafts 25 and 26 and carry respective clutch members 45 35 and 36 rigidly secured to their lower ends and adapted for engagement by clutch members 27 and 28, respectively, when the latter are elevated by lever 31. Shaft 34 carries at its upper end a pinion 37 which meshes 50 with a larger gear 38 secured on the upper end of a stub shaft 39. Shaft 39 carries near its lower end a gear pinion 40 meshing with a gear 41 on an upright shaft 42.

Shaft 33 carries a gear 43 meshing a gear 55 44 secured on a stub shaft 45 to which is also secured a pinion 46 meshing a gear 47 on the above mentioned shaft 42.

It will thus be seen that by throwing in 60 the clutch 27 the shaft 42 will be driven in one direction; while by throwing in clutch 28, shaft 42 will be rotated in the reverse direction and at a much slower rate of speed owing to the sizes and relations of the gears in the two trains of gearing.

Shaft 42 carries at its upper end a bevel

gear 48 which meshes with a bevel gear 49 mounted on the front end of a horizontal stub shaft 50 carrying at its rear end a bevel gear 51 which in turn meshes a bevel gear 52 secured to the lower end of a vertical 70 drive shaft 53. Shaft 53 is provided with a bevel gear 54 for each of the strip-carrying rolls. Any number of rolls may be operated from this shaft 53 or a plurality of such shafts may be similarly operated from 75 shaft 50 as will be readily understood.

Upper and lower rolls 55 and 56 are provided for each strip of display material used, and are respectively mounted upon transverse shafts 57 and 58 and frictionally operable thereby as will be presently set forth. The rolls are each provided with a metal strip 59 for securing the end of the display strip 60 to which removable slips 61 may be attached by side strips 62. Or the slips 65 may be pasted or otherwise secured to the fabric 60, or the information to be imparted printed, painted, or otherwise made an integral part of the strip 60.

Each roll has supported interiorly thereof, 80 a rock arm 63 having its end extended through a slot 64 in the end plate of the roll, and forming a finger 65 beyond said end plate for effecting automatic reversal of the rolls as will be presently described. A plunger 66 is attached to arm 63 and has its outer end seated in an aperture in the cylindrical wall of the roll. A spring 67 tends constantly to move the arm 63 so as to force the plunger 66 out and to move the finger 65 to the outer end of slot 64. The strip 60 when rolled on the roll will move plunger 66 to its inner position thereby moving finger 65 to the inner end of slot 64.

The upper shaft 57 is driven by a gear 68, and is provided with a screw threaded portion 69 upon which is mounted a nut 70 which may be forced into any desired degree of frictional contact with a washer 71 bearing on the end of roller 55 so that the roll 100 is driven with the shaft 57 but is also capable of being turned independently thereof.

The strip 60 is passed over idler rollers 72 at the front of the machine in passing from one to the other of the active rollers 115 55 and 56.

The shaft 58 is driven by a bevel gear 73 which meshes one of the gears 54. Mounted on the shaft 58 and to some extent underlying one end plate of the roll 56 120 is a ratchet wheel 74 which is engaged by a spring dog 75 mounted on the end of the roll 56 so that the roll is driven by the ratchet during downward movement of the strip but is free therefrom during the upward movement. A spring 76 bears against the opposite end of roll 56 so as to keep the strip constantly stretched tight.

The upper end of the shaft 53 is provided with a gear 77 which may be connected with 130

any suitable train of gearing (not shown) for rotating a phonograph record to effect the delivery of a lecture on the subject being displayed by the strip 60 and in syn-
 5 chronism therewith. The horn or delivery member of the phonograph is shown at 78. It will be understood that during the re-
 10 winding operation the operator will remove the stylus of the phonograph from the record, and upon again starting the winding operation, the stylus will be placed again on the record, or mechanical means may be provided for this purpose so that the operator would have only to change the records
 15 when necessary.

There remains only the reversing mechanism to be described. The rock lever 31 upon being moved in reverse directions effects operative connection of one or the
 20 other of the clutches 27 and 28 and disconnection of the other as above stated which effects either an upward display winding of strip 60 or a more rapid downward re-
 25 winding operation. As before stated, the rear end of rock lever 31 is projected rear-
 30 wardly beyond clutch 27 forming a finger 79 which extends through a rock arm 80 and carries at its rear end a roller 81 adapted to rest in one or the other of two notches
 35 82 formed in the front of a body 83 mounted on the lower free end of a plate spring 84, so that when lever 31 is thrown to either of its operative positions it will not easily be displaced.
 40 The rock arm 80 is straddled near its free end by the bifurcated lower end of a bar 85 to which it is pivotally secured. A spring 86 from the end of lever 80 to a suitable portion of the framework is provided to
 45 compensate for the weight of the various parts so that movement of bar 85 requires substantially the same force in either direction. The bar 85 is provided intermediate its ends with a sleeve 86' which is pivotally connected to a lever 87 at 88, said lever being itself pivoted to the framework at 89. By moving lever 87 by hand, the lever 31 may be thrown to either operative position or held in neutral intermediate position. A
 50 pin 90 on lever 87 is adapted to be engaged by a dog 91 when in neutral condition so as to lock the mechanism against operation. The upper end of bar 85 is pivotally connected to the lower of a pair of rock arms
 55 92 which are themselves pivoted at 93 to a suitable part of the frame and embrace at their free ends a rod 94 to which they are pivotally secured. Mounted in the upper and lower ends of bar 94 are plungers 95
 60 which are normally pressed outwardly by springs 96.

During normal winding and unwinding operations the fingers 65 of the rolls, above described, are in their inner positions, but
 65 when a roll is unwound, the respective

plunger 66 is released, and the respective finger 65 moved out into the path of the corresponding plunger 95. As the operation continues, the plunger 95 is forced in and then bar 94 is forced up or down as the case may be until roller 81 is nearly free from the notch 82 in which it has been standing and both clutches are inoperative. At this time, the force of the spring 86 comes into play to effect the slight movement necessary to throw the roller 81 over the high point into the other notch, and the reverse is effected.

While I have described what is deemed to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:

1. In a device of the class described, the combination of reversely driven shafts, a main driving shaft, clutch mechanism for effecting driving of said main driving shaft by either of said reversely driven shafts, a plurality of rolls driven by said main driv-
 95 ing shaft, a flexible strip operable by said rolls, and means supported in said rolls and controllable by said flexible strip to effect operation of said clutch mechanism.

2. In a device of the class described, the combination of a flexible strip carrying matter to be displayed, rolls secured to opposite ends of said strip, a main driving shaft, frictional driving means between said rolls and said main driving shaft, and means mounted in said rolls and controllable by said strip for automatically reversing the driving effect of said shaft, said means including a lever, and a bar mounted adjacent to said lever and extending into juxtaposition with said rolls.

3. In a device of the class described, the combination of a flexible strip carrying matter to be displayed, rolls secured to opposite ends of said strip, a main driving shaft, means operable by said main driving shaft for driving said rolls, reversely driven shafts each operable for driving said main driving shaft in a respective direction, clutch mechanism for rendering said reversely driven shafts operative and inoperative, a lever for operating said clutch mechanism, and means controllable by said flexible strip for operating said lever.

4. In a device of the class described, the combination of a flexible strip carrying matter to be displayed, rolls secured to opposite ends of said strip, a main driving shaft, means operable by said main driving shaft for driving said rolls, reversely driven shafts

- each operable for driving said main driving shaft in a respective direction, clutch mechanism for rendering said reversely driven shafts operative and inoperative, a lever for 5 operating said clutch mechanism, a bar mounted adjacent to said lever and extending into juxtaposition with said rolls, and means controllable by said strip for operating said bar.
- 10 5. In a device of the class described, the combination of a flexible strip carrying matter to be displayed, rolls secured to opposite ends of said strip, a main driving shaft, means operable by said main driving shaft 15 for driving said rolls, reversely driven shafts each operable for driving said main driving shaft in a respective direction, clutch mechanism for rendering said reversely driven shafts operative and inoperative, a lever 20 for operating said clutch mechanism, a bar mounted adjacent to said lever and extending into juxtaposition with said rolls, a push rod supported with its opposite ends arranged in operative relation to respective 25 ones of said rolls, and means supported by each of said rolls for automatically moving said push rod when said strip is unwound from the respective roll.
6. In a device of the class described, the combination of a flexible strip carrying matter to be displayed, rolls secured to opposite ends of said strip, a main driving shaft, means operable by said main driving shaft 30 for driving said rolls, reversely driven shafts
- each operable for driving said main driving shaft in a respective direction, clutch mechanism for rendering said reversely driven shafts operative and inoperative, a lever for operating said clutch mechanism, a bar mounted adjacent to said lever and 35 extending into juxtaposition with said rolls, a push rod supported with its opposite ends arranged in operative relation to respective ones of said rolls, spring-pressed plungers in said push rod, and levers supported by 40 each of said rolls and normally held out of co-operative relation with said plungers by said strip, and automatically operable to effect contact with a respective plunger upon 45 unwinding said strip from a respective roll. 50
7. In a device of the class described, the combination of a flexible strip carrying matter to be displayed, rolls secured to opposite ends of said strip, a main driving shaft, means operable by said main driving shaft 55 for driving said rolls, reversely driven shafts each operable for driving said main driving shaft in a respective direction, clutch mechanism for rendering said reversely driven shafts operative and inoperative, a lever 60 for operating said clutch mechanism, means controllable by said flexible strip for operating said lever, and a spring for maintaining said lever in either of its positions.
- In testimony whereof I have affixed my 65 signature.

RAFAEL PADILLA.
